UNITED STATES PATENT OFFICE.

WALDEMAR CHRISTENSEN, OF NEW YORK, N. Y.

TOY WAGON.

SPECIFICATION forming part of Letters Patent No. 718,192, dated January 13, 1903.

Application filed February 25, 1902. Serial No. 95,630. (No model.)

To all whom it may concern:

Be it known that I, WALDEMAR CHRISTENSEN, a citizen of Denmark, and a resident of New York city, Bronx, county and State of New York, have invented certain new and useful Improvements in Toy Wagons, of which the following is a specification.

This invention relates to a toy wagon so constructed that the various parts of the superstructure are rotated in different directions to obtain a pleasing variety of motion without the use of gearing.

The toy wagon when made on a large scale can be used for displaying advertisements.

In the accompanying drawings, Figure 1 is a perspective view of my improved toy wagon; Fig. 2, a longitudinal section thereof with parts of the flies broken away, and Fig. 3 a detail of the slotted bearing.

The letter *a* represents the fixed axle, *b* the wheels, and *c* the shaft, of a two-wheeled toy wagon. From the axle *a* project upwardly a pair of vertical shafts *d*, that extend above the wheels *b*. Upon these shafts are rotatably mounted a pair of drums or cylinders *e*, the heads *e'* *e''* of which are provided with perforations of such a size that the drums can slide upon the shafts. The lower drum-head or horizontal roller *e''* projects hori-

zontally over the rim of wheel *b* and is supported thereon, the wheel forming a seat for the drum. In this way the drum is always held firmly upon the wheel by gravity, and the vertical rotation of the latter is converted into a horizontal rotation of the former.

The upwardly-projecting end of each shaft *d* is provided with an upright slot *d'*, that forms the bearing for a transverse horizontal shaft *g*, projecting across the drums. The shaft *g* carries wheels *g'*, that engage the

outer portions of the drum-heads *e'*, and as the shaft is vertically movable in its bearings *d'* the wheels *g'* will always bear upon the drum-heads by gravity. Thus the horizontal rotation of the latter is converted into a vertical rotation of the former. The shaft *g* carries at its center a vane or fly *h*, which by the rotation of the shaft is made to rotate intermediate the drums.

Between the shafts *d* and the fly *h* the shaft *g* is embraced by two short rotatable sleeves *i*, having wheels *i'*. These wheels engage the inner portions of the drum-heads *e'*, so that the sleeves *i* are rotated in a direction opposite to that of the shaft *g*. Flies *j*, mounted upon the sleeves *i*, will accordingly be rotated in a direction opposite to that of fly *h*.

It will be seen that by drawing the toy wagon over the ground the drums *e*, flies *j*, and fly *h* will all be rotated in different directions, so that a pleasing variety of effects in motion is produced.

What I claim is—

A toy wagon composed of traction-wheels, a pair of drums in frictional contact therewith, a horizontal shaft, wheels mounted thereon that engage the outer portion of the drums, sleeves surrounding the shaft, and wheels on said sleeves that engage the inner portion of the drums, substantially as specified.

Signed by me at New York city, county and State of New York, this 24th day of February, 1902.

WALDEMAR CHRISTENSEN.
